UNITED STATES PATENT OFFICE

107,426

DESIGN FOR A TOILET BOTTLE

René Honnorat, Grasse, France, assignor to Molinard, Inc., New York, N. Y., a corporation of New York

Application September 10, 1937, Serial No. 71,550

Term of patent 3½ years

To all whom it may concern:

Be it known that I, René Honnorat, a citizen of France, residing at Grasse, France, have invented a new, original, and ornamental Design for a Toilet Bottle, of which the following is a specification, reference being had to the accompanying drawing, forming a part thereof.

The figure is a perspective view of a toilet bottle, showing my new design, the opposite sides of the bottle being plain.

I claim:

The ornamental design for a toilet bottle, as shown and described.

RENÉ HONNORAT.
